UNITED STATES PATENT OFFICE.

RICHARD H. TRESTED, OF GREENVILLE, NEW JERSEY.

INSOLE FOR BOOTS AND SHOES.

SPECIFICATION forming part of Letters Patent No. 284,092, dated August 28, 1883.

Application filed July 5, 1883. (No model.)

To all whom it may concern:

Be it known that I, RICHARD H. TRESTED, a citizen of the United States, residing at Greenville, in the county of Hudson and State 5 of New Jersey, have invented new and useful Improvements in Soles for Boots and Shoes, of which the following is a specification.

This invention relates to that class of insoles for boots and shoes which are provided with a 10 napped surface; and the object of my invention is to improve the construction and durability of such insoles, to lessen the cost of production, and to render them stiff and water-proof.

15 To these ends my invention consists in an insole composed of two thicknesses of canton-flannel, or similar textile material made with a napped surface, the nap being outside, and an intermediate thickness of buckram coated 20 with shellac, and cemented to the plain surfaces of the napped fabric.

In the drawings illustrating my invention, Figure 1 represents a plan or face view, and Fig. 2 a transverse sectional view, of the same.

25 In carrying out my invention I take a napped fabric—such as canton-flannel—and cut therefrom two pieces or thicknesses, *a*, *b*, in the required form for a sole. I then cut from a piece of buckram a thickness, *c*, corresponding in form to the napped pieces, and such buckram I coat with shellac or its equivalent,

and then cement the plain surfaces of the napped pieces upon opposite sides of the buckram, so that the nap will be outside or exposed. The three layers are united, preferably, by heat and pressure, and the shellac or its equivalent stiffens the entire insole and renders it water-proof. Instead of coating the buckram with shellac, and thus cementing the pieces or thicknesses together, I may use an 35 equivalent material, such as rubber cement. 40

By my invention I provide a simple, efficient, and durable insole with a nap on each side, and which is somewhat elastic to the foot, is water-proof, and can be worn for considerable 45 time without losing its softness.

Having thus described my invention, what I claim is—

An insole for boots and shoes, consisting of two pieces of canton-flannel or similar napped 50 fabric, with the nap on the outside, and an intermediate piece of buckram coated with shellac or its equivalent and cemented to the plain sides of the napped fabric, substantially as and for the purpose described. 55

In testimony whereof I have hereunto set my hand and seal in the presence of two subscribing witnesses.

RICHARD H. TRESTED. [L. s.]
